United States Patent Office

Des. 203,127
Patented Dec. 7, 1965

203,127

HOLDER FOR SALT AND PEPPER SHAKERS

Marvin T. Thurman, Cleveland, Ohio

Filed Jan. 18, 1965, Ser. No. 83,482

Term of patent 14 years

(Cl. D44—10)

FIG. 1

FIG. 2

FIGURE 1 is a perspective view of a holder for salt and pepper shakers showing my new design;

I claim:

The ornamental design for a holder for salt and pepper shakers, substantially as shown.
